UNITED STATES PATENT OFFICE.

ARTHUR L. BROWN, OF WILKINSBURG, PENNSYLVANIA, ASSIGNOR TO WESTINGHOUSE ELECTRIC AND MANUFACTURING COMPANY, A CORPORATION OF PENNSYLVANIA.

IMPREGNATING PROCESS.

1,248,447.

Specification of Letters Patent.

Patented Dec. 4, 1917.

No Drawing.

Application filed December 10, 1914. Serial No. 876,438.

To all whom it may concern:

Be it known that I, ARTHUR L. BROWN, a citizen of the United States, and a resident of Wilkinsburg, in the county of Allegheny and State of Pennsylvania, have invented a new and useful Improvement in Impregnating Processes, of which the following is a specification.

My invention relates to processes of impregnating cloth and other absorbent material, and it has special reference to processes of impregnating such materials with varnish in order to render them waterproof and suitable for electrical insulating purposes.

The object of my invention is to provide an impregnating process of the above indicated character by means of which absorbent materials may be impregnated quickly and easily, and by which a saving in materials and expense may be effected over the processes heretofore employed.

Cloth, paper and similar material is usually impregnated with varnish by immersing the fabric in a bath composed of a drying oil and a varnish gum, boiled linseed oil and gum copal being commonly employed for this purpose. The varnish is thinned to the proper consistency for application to the fabric with benzine or other suitable solvent. After one or more applications of the varnish, the fabric is baked, and the solvent is thereby evaporated and lost.

According to my present invention, I omit entirely the use of a volatile thinner by successively applying the several varnish ingredients, each of which is sufficiently thin to be applied without the addition of solvent. The materials which I employ are, first, a raw drying oil, such as linseed oil or Chinese wood oil, and second, a drier which may be any of the well known commercial driers, such, for example, as those composed of lead-manganese resinate or tungate or mixtures of these substances. I may treat the fabric first with the drier and then with a separate application of the raw drying oil; or I may first apply the drying oil to the fabric and afterward apply the drier. At present, however, I prefer to treat the cloth first with the drier and then with the oil. The drier absorbed by the cloth appears to effect sufficient polymerization of the oil in the presence of air, to give a coating similar

to the varnish coating produced by present methods.

Any suitable manipulations may be employed for subjecting the cloth or other fabric to successive applications of the drier and the oil. For example, a web of cloth may be run through a bath of drier and then through one or more baths of the oil, and these operations may be carried out in any of the well known impregnating machines. The temperature at which the operations are performed, and the length of time during which the material is immersed in the successive treating baths, do not differ materially from the ordinary conditions of fabric impregnation and may readily be controlled by operatives having ordinary skill. After the fabric is treated in the manner described above, it is subjected to the action of dry heat by baking it in the usual manner.

The particular substances mentioned above are referred to only for the purpose of illustration, and I do not wish to be restricted to their use. In the subjoined claims, therefore, the expressions "polymerizing agent" and "polymerizable substance" are to be understood as referring to every kind of drier and every kind of drying oil which are available for use in the arts. It is also to be understood that the claims which specify that the drying oil and drier are applied "successively" are intended to cover the modification of my process in which the drier and oil are applied in the order named and also the modification in which the oil is applied first and the drier afterward. In view of the numerous modifications which may be effected in my process, within the scope of my invention, I desire that only such limitations shall be imposed upon my invention as are indicated in the appended claims.

I claim as my invention:

1. A process of impregnating absorbent material that comprises successively applying to the said material a polymerizable liquid and a polymerizing agent.
2. A process of impregnating absorbent material that comprises applying a polymerizing agent to the said material and then applying a polymerizable liquid to the said material.
3. A process of impregnating absorbent material that comprises successively apply-

- ing to the said material a drying oil and a drier.
4. A process of impregnating absorbent material that comprises applying a drier to the said material and then applying a drying oil to the said material.
5. A process of impregnating absorbent material that comprises successively applying to the said material a raw drying oil and a drier.
- 10 6. A process of impregnating absorbent material that comprises applying a drier to the said material and then applying a raw drying oil to the said material.
- 15 7. A process of impregnating absorbent material that comprises passing the said material through successive baths of a drying oil and a drier.
8. A process of impregnating absorbent material that comprises passing the said material through a bath of a drier and then through a bath of a drying oil.
- 20 9. A process of impregnating cloth that comprises passing the cloth through successive baths of raw linseed oil and a drier.
- 25 10. A process of impregnating cloth that comprises passing the cloth through a bath of a drier and then through a bath of raw linseed oil.
11. A process of impregnating cloth that comprises passing the cloth through successive baths of raw linseed oil and a drier, and then applying dry heat to the treated cloth.
12. A process of impregnating cloth that comprises passing the cloth through a bath of a drier, then passing the cloth through a bath of raw linseed oil, and finally applying dry heat to the treated cloth.
13. A process of impregnating cloth that comprises passing the cloth through a bath of a drier, then passing the cloth through a plurality of baths of a drying oil, and finally subjecting the treated cloth to dry heat.
- 45 In testimony whereof I have hereunto subscribed my name this 28th day of Nov., 1914.

ARTHUR L. BROWN.
